UNITED STATES PATENT OFFICE.

EDWARD C. TERRY, OF HARTFORD, CONNECTICUT.

ROTARY WATER-METER.

SPECIFICATION forming part of Letters Patent No. 256,409, dated April 11, 1882.

Application filed October 24, 1881. (Model.)

To all whom it may concern:

Be it known that I, EDWARD C. TERRY, of Hartford, in the county of Hartford and State of Connecticut, have invented certain new and useful Improvements in Water-Meters, of which the following is a specification.

My invention relates to water-meters in which an oval float has both a longitudinal and rotary motion within a cylindrical case, and in which other peculiar features are found, as hereinafter described; and the objects of my invention are efficiency, simplicity, and cheapness. I attain these objects by the mechanism illustrated in the accompanying drawings, in

15 which—

Figure 1 is a plan view with the cap-plate removed; Fig. 2, a vertical section on line xx of Fig. 1. Fig. 3 is a plan view of the inner face of the cap-plate; Fig. 4, a plan view showing a modification of the float. Fig. 5 is a perspective view, partly in section, and showing the float in broken lines.

A designates a cylindrical case or chamber, having an enlargement, a , at one side; B, a cylindrical post stationarily affixed within the case A, and C an oval and hollow float. The inside of the float C has semi-cylindrical walls at each end and straight walls upon the sides, between said cylindrical walls. The float is placed within the case and over the cylindrical post, the diameter of which is equal to the distance between the opposite inner walls on the two longest sides of the float. The post is made a little shorter than the vertical length of the inside of the case, so that a slotted cross-piece, b , may extend over the top end of the post, as shown. Near one edge of post B, at its upper end, I place a pin or stud, c , upon which to mount a shaft, k , which is flattened or provided 40 with a cross-piece at the bottom which fits the slot in the cross-piece b . Near the middle of the enlargement a is a thin plate or cut-off, d , the inner edge of which extends into the case a little farther than would the cylindrical wall 45 thereof if continued wholly around the case. A thin horizontal guide-plate, m , about half-way between the top and bottom of the case, extends from the inner edge of the cut-off d to the cylindrical wall of the case upon the in- 50 fluent side of the cut-off. The water is let in and out at both top and bottom, the same entering the vertical passage e from a horizontal

pipe leading thereto, and discharging through a like passage, f , and into a horizontal pipe connecting thereto, the broken circle in Fig. 2 55 indicating the point of connection with the passages e f and said pipes. The horizontal pipes which lead to the passage e and from the passage f are also indicated by broken lines in Fig. 5. From the ends of the vertical passages 60 channels g h lead through the cap D and the bottom portion of the case to the interior, the form of which channels is most clearly shown in Figs. 3 and 5. The portions of said channels which are cut off or hid from view in the section Fig. 2 are indicated in broken lines. 65

The operation is as follows: When the float is in the position represented in the drawings both ends of the float are in contact with the side walls of the case, and the measuring-chamber, which is upon the outside of the float, is then closed, because the inlet and outlet channels g h do not extend quite to that side of the float upon which said chamber lies. When the float is at this point the water freely 70 enters inside of it, also the outside at the enlargement a , and the line of pressure upon the float is indicated by the broken line y y . The water in pressing upon the float acts substantially the same as if it in fact pressed upon 75 the plane indicated by line y y , and it is for this reason that I term said plane the "line of pressure." So soon as the rear end of the float approaches the enlargement a the water begins 80 to discharge. The measuring-chamber which 85 is inside of the float is closed when the longest axis of the float is in line with the cut-off d , so that both measuring-chambers are never closed at the same time. Another position of the float is indicated in Fig. 1 by the broken 90 lines describing an oval, and the line of pressure at that point is indicated by the broken line z . In all the various positions of the float one point of it is in contact with the cut-off and one point with the cylindrical wall of the 95 case. The slotted cross-piece moves from side to side with the float, sliding by the flattened portion of the shaft k , which cannot rotate within the slot, and thereby must rotate with the float, so that the shaft makes one revolution 100 for every revolution of the float, and thereby furnishes means for the attachment of any ordinary registering mechanism to register the number of revolutions of the float or the

amount of water measured. The cross-piece also somewhat assists in properly guiding the movements of the float; but it is principally for the purpose of furnishing means to connect the registering apparatus with the float. The guide *m* prevents the end of the float from working into the enlargement *a* so far as to withdraw its opposite end away from the cylindrical wall of the case. I prefer to make the float of hard rubber and the other parts of brass.

The meter may be operated by admitting the water from only one side; but it is best to admit it from both top and bottom.

If desired, instead of making the post *B* stationary, it might be flattened upon opposite sides and fitted to the inside of the float, as shown in Fig. 4, when it could be mounted so as to revolve on its axis and impart precisely the same motion to the float as before described.

I claim as my invention—

1. In a water-meter, the combination of a cylindrical case, having an enlargement at one side, with an oval float having both a longitudinal and rotary movement within said case, substantially as described, and for the purpose specified.

2. The combination of the cylindrical case, the hollow oval float, the post *B*, and the cut-off *d*, substantially as described, and for the purpose specified.

3. The combination of the cylindrical case having the enlargement *a*, the float *C*, post *B*, cut-off *d*, and guide *m*, substantially as described, and for the purpose specified.

4. The combination of the case *A*, oval float *C*, slotted cross-piece *b*, shaft *k*, and post *B*, substantially as described, and for the purpose specified.

5. The combination of the case *A*, oval and hollow float *C*, post *B*, and outlet and inlet channels *g h*, located with reference to the end of the float substantially as described, and for the purpose specified.

6. In a water-meter, the passages *e f*, with the transverse inlet and outlet channels at both ends thereof leading to and from the interior of the case, substantially as described, and for the purpose specified.

EDWARD C. TERRY.
